UNITED STATES PATENT OFFICE.

NATHANIEL P. WALLACE, OF YPSILANTI, MICHIGAN.

CHILD'S CLOSET-SEAT.

982,553.

Specification of Letters Patent. Patented Jan. 24, 1911.

Application filed May 5, 1910. Serial No. 559,566.

To all whom it may concern:

Be it known that I, NATHANIEL P. WALLACE, a citizen of the United States, residing at Ypsilanti, county of Washtenaw, State 5 of Michigan, have invented a certain new and useful Improvement in Children's Closet-Seats, and declare the following to be a full, clear, and exact description of the same, such as will enable others skilled in the 10 art to which it pertains to make and use the same, reference being had to the accompanying drawings, which form a part of this specification.

My invention relates to child's closet 15 seats, and consists in the various arrangements and combinations hereinafter pointed out and claimed.

Its object is to provide a seat having a permanent location in connection with and 20 adjacent to an ordinary closet seat in such manner that it will be available for use when required and yet having a fixed position and be out of the way when not desired. I accomplish this by the arrangement and 25 combinations hereinafter stated.

In the drawings,—Figure 1, is a front elevation of an ordinary closet bowl and seat with the adjacent child's seat folded and arranged when not in use. Fig. 2, is a front elevation of the child's seat arranged 30 and adapted for use. Fig. 3, is a side elevation or view of the same parts with the child's seat in position for use and viewed from the side opposite its permanent position 35 when not in use. Fig. 4, is a plan view of the same when in position for use. Figs. 5, 6, 7, show details of the arrangements.

In the drawings similar letters refer to similar parts.

40 A represents the bowl of an ordinary water closet; B the lid or cover therefor; C the seat; all of which are of any approved construction.

45 D, D, are a pair of slotted standards having a curved top d; E is the child's seat folded. At each of the two lower corners thereof are projections or ears F, which are adapted to slide vertically outside of the two curved standards D, D; passing through each ear is a long bolt G which also passes through the slots of both of the standards D, D, and by this means the assembled seat E is slidily pivoted in the slots and can be 50 raised vertically therein and then turned over and dropped down upon the seat C of the bowl A, as shown in Fig. 2. In order to

hold the assembled seat E in proper position I have provided a bolt connecting the two curved ends of the slotted standards at d¹, d¹; a metal bracket attached to the back 60 of the assembled seat E, lettered H, Fig. 7, is adapted to shut down over this bolt, the end being turned down to form a hook, as shown at h. This prevents the assembled seat from dropping down upon the floor, 65 turning upon the pivot G; a curved button J is adapted to swing around under the bolt d¹, and prevent the assembled seat from being raised until the button is swung out of engagement with the bolt or bar d¹. 70

The child's seat consists of a seat proper C¹, a back C² hinged thereto and adapted to be folded down thereon; two side pieces C³, C³ which are exactly alike except that they are right and left, also hinged to the seat 75 C¹, and adapted to be folded down thereon, and a front bar or piece C⁴, which has two slotted ears K, K, adapted to engage small bolth k, k, having wing nuts thereon; by these means the bar C⁴ can be drawn away 80 from the seat C¹ substantially as shown in Fig. 3, and this can be turned upon the bolts k, to a position which will hold a child from falling out from the seat formed by the recess of the two winged pieces C³, C³, 85 and the back C². Also by means of the wing nuts it can be fastened in any position that is suitable to that purpose.

The operation of my invention is quite 90 obvious from the description, it being noted that the slotted standards D, D, are permanently fastened to the floor of the room and at one side of the bowl A and seat C as shown in Fig. 1. When desired to be used the assembled seat E is detached from the 95 curved bolt at the top of the standard as described and then drawn up vertically controlled by the slots in the standards until the pivotal point reaches the curves in the slots. It is then dropped down upon the ordinary seat C of the bowl and in this position the back thereof C² and the side pieces C³, C³, are raised, the side pieces holding the back 100 in position, and the bar C⁴ is properly adjusted for use. When it is not desired for use the reverse of this operation takes place, the assembled seat E is folded and dropped down in the position shown in Fig. 1, and latched therein until it is desired to be used 105 again; when in such position it is out of the way and yet it is always ready to be used when desired. 110

Having thus described my invention what I desire to claim is:

1. The combination of an ordinary closet bowl and seat, sustaining means as a floor, slotted curved standards fixed to such sustaining means and adjacent to said bowl, a child's seat, means pivoting the same to said standards, said pivotal means having a sliding engagement with the slots thereof whereby the said seat may be drawn upward and dropped or folded down horizontally upon the seat of the bowl, substantially as described.
2. In a child's seat, the combination of two slotted standards, a seat slidingly pivoted therein, detachable means for engaging and holding said seat in a vertical position,

and means for holding said seat when raised, in a horizontal position for use, substantially as described.

3. In a child's closet seat, the combination of fixed vertical slotted standards having curved slots therein, a seat slidingly pivoted in said slots, folding side pieces to said seat, and a foldable back to said seat, and a guard slidingly pivoted to said seat, substantially as described.

In testimony whereof, I sign this specification in the presence of two witnesses.

NATHANIEL P. WALLACE.
